(57) **CLAIM**

The ornamental design for a guide rails for a tarpaulin cover of a commercial vehicle, as shown and described.

DESCRIPTION

FIG. 1 is a top plan view of the guide rails for a tarpaulin cover of a commercial vehicle of the present invention.

FIG. 2 is a first perspective view thereof;

FIG. 3 is a second perspective view thereof;

FIG. 4 is a left side elevational view thereof;

FIG. 5 is a right side elevational view thereof;

FIG. 6 is a bottom plan view thereof; and,

FIG. 7 is a front elevational view thereof, with the rear elevational view being the mirror image of.

1 Claim, 4 Drawing Sheets
